UNITED STATES PATENT OFFICE.

HOMER L. BOYLE, OF GRAND RAPIDS, MICHIGAN.

VEHICLE.

SPECIFICATION forming part of Letters Patent No. 470,175, dated March 8, 1892.

Application filed April 18, 1891. Serial No. 389,429. (No model.)

To all whom it may concern:

Be it known that I, HOMER L. BOYLE, a citizen of the United States, residing at Grand Rapids, in the county of Kent and State of Michigan, have invented a new and useful Improvement in Vehicles, of which the following is a specification.

My invention relates to vehicles and cars, and has for its objects the provision of means by which they may be operated by the use of steam or vapor engines or other motive power. I attain these objects by the mechanism illustrated in the drawings, in which—

Figure 1 is a sectional view of the running-gear and my devices for operating the same, the body of the car located thereon and partially cut away to show its interior construction and arrangement. Fig. 2 is a top view of the running-gear of a car with the bed-plate and the several devices constituting my invention for operating the same, being the same as Fig. 1, except that the body of the car has been removed. Fig. 3 is a front and detail view of the forward truck of the car with its axle, gearing, and sprocket-wheel. Fig. 4 is a top view of the running-gear of a vehicle provided with a bed-plate, motive power, and the various devices constituting my invention for operating the same. Fig. 5 is a detail view of the friction-gearing employed for my device. Fig. 6 is a detail view of a band provided with friction-rollers. Fig. 7 is a sectional view upon the lines xx of Fig. 4 and is provided with a representation of the body of the carriage and springs.

In my invention I employ as the motive power a steam or gas engine, motor, or other power that can be used for giving reciprocal or rotary motion. I prefer to employ a gas-engine such as that described in my pending application for Letters Patent of the United States, filed March 2, 1891, Serial No. 383,501, and in the accompanying drawings I have shown that form of engine.

The letters A represent the ordinary car-wheels or wheels of a vehicle attached to their axles C.

The letter B' represents the bed-plate. The bed-plate rests upon the axle of the rear wheels by means of collars or sleeves and a

king-bolt through the front axle or by means of supports, as shown in Figs. 4 and 7.

P represents the cylinder of the engine.

P' P' represent the two guiding-bars which control the head of the piston-rod P''', the piston being located centrally between the two guide-bars P'. The pitman P'' is pivotally connected to the piston-rod P''' and to the wheel N by a crank-pin, so that as the piston-rod reciprocates it causes the wheel N and its connections to rotate in a given direction. The wheel N and the gear-wheel M are rigidly fixed upon the shaft S, which is supported in bearings in the brackets T T'. This shaft S carries a pinion G, which fits loosely thereon and is held in place by a collar 1, and a bracket T', it being so located as to mesh with the gear-wheel H. The pinion G is provided with a hub or shank, which extends in a conical form to be received and fitted into a sleeve G', which is located upon the shaft S. The sleeve is provided with a groove, in which fits a spline upon the shaft, so that the sleeve G is capable of longitudinal motion upon the shaft, but is otherwise firmly affixed thereto. In the exterior surface of the sleeve G' is cut a groove g, in which is fitted a lug g', which is attached to a lever F', pivotally fastened to the bed-plate at f', the upper end of this rod or lever being connected by rods with a hand-lever L', so that by the movement of said lever L' the clutch-sleeve G' may be forced upon the conical projecting hub of the pinion G, which will be caused to accept the corresponding motion of the sleeve.

Rigidly attached to the rear axle C is the gear-wheel H, which, as already explained, meshes with the pinion G and also meshes with the gear-wheel I, whose journals are supported in bearings n. Upon the upper surface of this bevel-gearing I is rigidly attached a sprocket-wheel, upon which is operated an endless chain J, which connects with a corresponding sprocket-wheel rigidly attached to the bevel-gearing I', which meshes with the gear-wheel H', located upon the front axle of the car. The two bevel-gearings I I' and their respective sprocket-wheels are located at the exact center of their respective axles.

For the purpose of controlling the speed of the car and causing it to reach a maximum or minimum speed instead of using the gear-wheel H in the form shown in Fig. 2 a gear-wheel with two or more sets of gearing, as shown in Figs. 4 and 7, may be employed, and the pinion G may be provided with a peripheral groove and means for causing it to recede from or approach the axle C, so as to engage with either series of teeth of the several gearings.

For the purpose of guiding the car and enabling the front truck to conform to the curve in the track I have provided means for communicating power to the wheels of the front truck and also causing it to turn upon the central king-bolt, which sustains it in place. Upon the upper surface of the gear-wheels I I' are located integrally or permanently the sprocket-wheels 4 and 5, the centers of which correspond exactly to the centers of the axles C C, and the power communicated to the sprocket-wheel 4 is communicated to the sprocket-wheel 5 by an endless chain J, as above set forth, and it will be seen that this power will operate the front wheels A whether the front axle is parallel with the rear one or is on a variant line therewith, the sprocket-wheel 5 operating the gear-wheel I', which meshes with the gear-wheel II', which is permanently affixed to the front axle C. Held and supported firmly by brackets R R', which are firmly attached to the bed-plate, is the journal 3, provided with a pinion M', which meshes with the gear-wheel m. Upon the shaft 3 at its front end is located a double friction-gearing d, which is provided with a spline or feather fitting in a groove or keyway in the shaft 3 and being capable of longitudinal motion upon but revolving with the sleeve 6. Upon the hub or sleeve of the gearing d is placed a sleeve or collar 7, and it is held at approximately the center of the sleeve by the two coiled springs located, respectively, upon each side of said sleeve or collar. Pivotally attached to the sleeve or collar 7 is a lever F, which is pivotally attached to a bracket fastened to the bed-plate B', as shown in Fig. 1. At the upper extremity of this lever F it is connected by a rod with a lever L, so that by the operation of that lever the collar 7 may be moved forward or backward upon the sleeve 6, causing the double friction-gearing d to move longitudinally in one or the other direction upon the shaft 3. Interposed between the two sections of the double friction-gearing d is a friction-pinion d', supported upon the axle 8, which is held in bearings attached to the bed-plate B'. This shaft 8 is provided with a screw-thread 9, which engages with the spur-gear B. The spur-gear B is supported upon a shaft 10, the lower end of which is located in a bearing in the bed-plate and the upper portion of which is supported by the lug 11, attached to the permanent post 12. Beneath the spur-gear B and upon the same shaft is located a sprocket-

wheel 13, engaging with a chain i i, which is attached to the extreme ends of the front axle C by means of springs i' i'.

Instead of employing the clutch device G and G' for communicating the motive power to the gearing located upon the axles of the vehicle or car, there may be employed throughout the double friction-gearing devices already referred to with reference to the steering or guiding mechanism, as above illustrated and described. In Fig. 4 the arrangement of the motive power is the same as that already described, except that it is located in a direct line with the movement of the vehicle and the primary motion or power is communicated to the shaft 14, as is shown. This shaft 14 is held in position and carries its various devices by means of brackets, which are firmly affixed to the bed-plate of the vehicle. There is located upon it a double friction-gearing D, with its hub or sleeve and the sleeve or collar upon said hub and supported on each side by two coiled springs, as shown. At the extreme end of the shaft 14 is located the conical friction-pinion D', so adjusted as to easily engage the double friction-gearing D. Upon the axle C, Fig. 4, is located the gear-wheel H, which, as is shown, is provided with a central bevel-gearing and two exterior horizontal gearings, this gear-wheel H being firmly attached to the axle C. Journaled in the clip or hanger W' and in the bracket E' is located the shaft E. Upon the rear end of this shaft is placed the pinion G, provided with a heel or hub containing a spline, which fits in a longitudinal groove in the shaft, so that the pinion G is capable of longitudinal movement toward and from the axle C and may be made to engage with the central bevel-gearing or the external gearings of the gear-wheel H. This movement is effected by a rod f, connected with the pinion G by means of the lever F' and the V-shaped portion F'', pivotally attached to said lever F'. The movement of the double friction-gearing D is controlled by a rod 15, pivotally connected with the lever L' and the pawl and ratchet R. Supported in brackets e' e', which are firmly attached to the bed-plate B', is the shaft e, carrying at its rear end the conical friction-pinion d' and at its reverse end the bevel-pinion g, which latter engages with a pinion i upon the shaft 8, provided with a screw-thread 9, that engages with the teeth of the sector j.

The angular lever a' is pivoted to the bed-plate at 16, and its Y-shaped end grasps and holds the collar or sleeve supported upon the hub of the double friction-gearing d between the respective springs upon said hub, as shown. The rod f, which is also pivotally connected with the angular lever a', is attached to an arm at the base of the lever L, which is journaled in the bed-plate and also in a bearing in plate 17. The plate 17 is provided with openings into which a pin which is operated by the lever L is admitted, so as

to hold the parts in any given position, the lever L being provided with a crank-arm, as shown. The lever F' is connected with the lever K, as shown, which may be operated by the foot.

Having thus described the various parts of the device constituting my invention, I now explain its mode of operation.

It is intended that the engine or motive power need not stop or be started or slowed up every time the vehicle is started or stopped or slowed up, but that the power shall be communicated to or cut off from the operating devices of my invention by means of the clutch G' and the hub of the pinion G or by changing the position of the double friction-wheel D in its bearing upon the conical friction-wheel D'. When the operator desires to start the vehicle or car, he seizes the lever L' and forces the sleeve G' upon the conical point of the hub of the gearing G. The motion of the wheel M, which is operated by the pitman and wrist-pin of the engine, at once communicates its motion to the pinion G, which, meshing with the gear-wheel H, communicates motion to the axle C and the wheel A, which are rigidly attached to it. This motion is also communicated to the gear-wheels I, and, by means of the sprocket-wheel 4 and the endless chain J, to the sprocket-wheel 5, and thence to the gear-wheel H', permanently located upon the front axle. It is evident that when the operator desires to stop the motion of the car he reverses the lever L' and disengages the clutch, so that while the motion of the wheels M and N may continue the pinion G ceases to rotate or communicate power. In like manner when it is desired to cause the front axle and wheels to conform to a curve of the track or to change the direction of the vehicle, as the case be, the operator employs the lever L, causing the lever F to press one of the interior faces of the double friction-gearing d against the conical friction-pinion d', thereby communicating motion to it and the shaft 8, upon which is located the screw-thread 9. This engages the spur-gear e and, by means of its sprocket-wheel and the sprocket-chain i, causes the axles of the front wheels to conform to the curve of the track to the right or left, as the case may be, the springs i' enabling the front wheels to conform to any slight variation or irregularity in curvature. As already suggested, instead of employing the clutch device, as shown in Fig. 2, the double friction-gearing, as shown in Figs. 4 and 7, may be employed. In such case the lever L' is operated, causing the double friction-gearing D to move upon the shaft E and one of the interior faces of its bevel-gearing to come in contact with the conical bevel-pinion D', which receives its motion from the cylinder P through the piston and pitman-rod and the wheel O. It is evident that a forward or reverse motion may be thus communicated to the double friction-gearing D,

depending upon which of its faces is brought into frictional contact with D'. The motion of the shaft E communicates motion to the bevel-pinion G, which, meshing with the gearing H, communicates motion to the axle C and the wheels A, located upon it.

It is important that some means shall be provided for graduating the speed of the car or vehicle, while the power of the engine or cylinder may remain constant. This is effected by a gear-wheel H, which has one or more exterior gearings capable of meshing with the pinion G, and the gearing G may be made to mesh with either of these gearings by means of the lever K and the lever F'. The pinion G, being capable of longitudinal motion on the journal E, may be retracted, so as to mesh with either series of teeth in the compound gear-wheel H. The lever L' is provided with the ordinary pawl and ratchet, so as to hold it in any given position. For the purpose of changing the direction of the front axle and wheels the double friction-gearing d, meshing with the friction-pinion d', communicates motion through the pinion g to the shaft 8, and the screw-thread 9, engaging the sector j, changes the direction of the axle C. This is effected by means of the lever L and rod f operating the angle-lever a' and causing the double friction-gearing d to move backward and forward upon the shaft 14. The position of this steering device is retained by means of a pin operated by the hand-lever e, that engages the openings in the plate 17. As the sleeves or collars a and 7 require considerable force for their operation, and are consequently liable to considerable wear, I insert on each side of them between the adjacent springs 105 anti-friction rollers, as shown in Figs. 5 and 6, the construction of which is apparent.

It is evident that there may be changes and modifications in the construction of many parts and their arrangement in my invention without departing from the spirit thereof. Thus the gear-wheel of the rear axle may be loose instead of fixed, and the clutch, instead of being located upon the power-supplying shaft and engaging the hub G, may be located upon the rear axle and engage with a hub of the gear-wheel H, whereby that gear-wheel may be made to revolve. I therefore do not limit myself to the specific construction shown.

Having therefore described my invention, what I claim as new, and desire to protect by Letters Patent, is—

1. In a car or vehicle, a bed-plate supported on the two axles thereof and their wheels, each axle provided with a fixed gear-wheel, and means for communicating the motion of the fixed gear-wheel on one axle to that on the other, in combination with a power-supplying shaft provided with a loose gear-wheel meshing with the gear-wheel of the rear axle, also with a clutch adjustable longitudinally on said shaft and revolved therewith by means of a spline and groove, a lever operating said adjustable sleeve or collar, so as to engage or

disengage said clutch with said loose gear-wheel, and means for operating and revolving said shaft and the devices affixed thereto, all substantially as shown.

- 5 2. In a car or vehicle, a bed-plate supported on the axles thereof and their wheels, each axle provided with a fixed gear-wheel, and means for communicating the motion of the fixed gear-wheel on one axle to that on the other, in combination with a power-supplying shaft provided with a gear-wheel meshing with the fixed gear-wheel of the rear axle, also with a clutch adjustable longitudinally on said shaft and revolving thereon by means of a spline and groove, said clutch provided with an annular groove, a lever engaging in said groove and operating said adjustable clutch, so as to engage or disengage the same with or from said loose gear-wheel, brackets attached to said bed-plate and supporting said power-supplying shaft in place, and means for operating and revolving said shaft and the devices affixed thereto, all substantially as shown.
- 15 3. In a car or vehicle, a bed-plate supported by collars or hangers upon the rear axle and its wheels and pivotally attached to the front axle and its wheels at and above the center of said axle, said axles each provided with a gear-wheel, in combination with two compound gear and sprocket wheels, each meshing, respectively, with said gear-wheels of the axles, and the sprocket-wheels connected and operated uniformly by an endless chain, the compound gear and sprocket wheels supported by vertical journals and bearings, whereby the motion or revolution of the gear-wheel of the rear axle is communicated to that of the front axle unaffected by any change of direction of the front axle, all substantially as shown.
- 25 4. In a car or vehicle, a bed-plate supported by collars or hangers upon the rear axle and its wheels and pivotally attached to the front axle and its wheels at the center of said axle, said rear axle provided with a fixed gear-wheel, in combination with a shaft supported by brackets, said shaft provided at one end with a gear-wheel meshing with said pinion and revolving with it by means of a spline and groove, a rod and lever connected to said adjustable gear-wheel, a double friction-gearing provided with a sleeve carried upon said shaft and adjustable longitudinally thereon, but revolving with it by means of a spline and groove, a power-supplying shaft provided with a friction-pinion at one end engaging said double friction-gearing, and means for operating and revolving said power-supplying shaft and the several parts engaging and connecting therewith, all substantially as shown.
- 35 5. In a car or vehicle, a bed-plate supported on the axles and wheels thereof, the rear axle provided with a compound gearing having more than one series of gear-teeth, in combination with a shaft carrying at one end an adjustable pinion with beveled and horizontal

teeth capable of engaging either series of the fixed gearing of the axle, a lever connected to said pinion by a rod, whereby said adjustable pinion may be controlled and made to mesh with either series of teeth in said compound gearing, all substantially as shown.

6. In a car or vehicle, the combination of a gear-wheel rigidly affixed to the rear axle of said car or vehicle with a shaft supported by brackets attached to the bed-plate thereof, said shaft provided with a gear-wheel meshing with that of said axle and supporting a double gearing longitudinally adjustable upon said shaft by means of a collar and springs and a rod and lever, a power-supplying shaft provided with a pinion engaging said double gearing, and means for operating and revolving said power-supplying shaft, all substantially as shown.

7. In a car or vehicle, the combination of a gear-wheel rigidly affixed to the rear axle of said car or vehicle with a shaft supported by brackets attached to the bed-plate thereof, said shaft provided with a gear-wheel meshing with that of said axle and supporting a double friction-gearing longitudinally adjustable upon said journal by means of a collar and springs and a rod and lever, a power-supplying shaft provided with a friction-pinion engaging said double-friction gearing, and means for operating and revolving said power-supplying shaft, all substantially as shown.

8. In a car or vehicle, the combination of a shaft provided with a pinion meshing with the gear-wheel of the rear axle and carrying a longitudinally-adjustable double friction-gearing, a power-supplying shaft provided with a friction-pinion and having a longitudinally-adjustable double friction-gearing engaging with a friction-pinion, and means for changing and controlling the line or direction of the front axle and its wheels, all substantially as shown.

9. In a car or vehicle, the combination of a power-supplying shaft supported by brackets attached to the bed-plate, provided with a longitudinally-adjustable double friction-gearing held in place and adjustable upon said shaft by means of a sleeve or collar and adjacent springs and a rod and lever connected to said sleeve or collar, a shaft carrying at one end a friction-pinion engaging with said double friction-gearing and at the other end a beveled gear-pinion, a cross-shaft with a beveled gear-pinion meshing with said last-mentioned pinion and provided with a screw-thread engaging the teeth of a sector attached to said front axle, and means for operating and revolving said power-supplying shaft, whereby the line and direction of said front axle may be changed as desired, all substantially as shown.

10. In a car or vehicle, a power-supplying shaft connected to the engine or motive power by a pitman, crank, and crank-pin, provided with an adjustable double gearing and a pinion, in combination with an operating-shaft

having a longitudinally-adjustable gearing and connected by gearing with the rear axle, and a steering or guiding shaft provided with a pinion and connected by gearing with the 5 front axle, whereby the motive power may operate the rear axle and wheels and also change the direction of the front axle and wheels, all substantially as shown.

11. In a car or vehicle, a power-supplying 10 shaft connected to the engine or motive power by a pitman, crank, or crank-pin, provided with an adjustable double friction-gearing and a friction-pinion, in combination with an operating-shaft having a longitudinally-adjustable double friction-gearing and connected 15 by gearing with the rear axle, and a steering or guiding journal provided with a friction-pinion and connected by gearing with the front axle, whereby the motive power may operate 20 the rear axle and wheels and also change the direction of the front axle and wheels, all substantially as shown.

12. The combination of a shaft carrying at one end a longitudinally-adjustable beveled 25 pinion with a double frictional gearing provided with a hollow hub fitting upon said shaft and capable of longitudinal adjustment, but held in rotation with said shaft by means of a groove and a spline in said hub, a collar 30 or sleeve upon the central portion of said hub, adjustable thereon, but firmly supported by spiral springs on either side thereof, an angular rod or arm connected with said sleeve or collar, and a lever to which said angular 35 rod or arm is connected, whereby said double frictional gearing can be adjusted longitudinally upon its shaft and caused to engage with a frictional pinion interposed between its interior faces, all substantially as shown.

13. In a car or vehicle, a power-supplying 40 shaft supported by brackets attached to the bed-plate, provided with a double gearing longitudinally adjustable upon said shaft by means of a sleeve or collar and supporting-springs and a lever connected with said sleeve 45 or collar, in combination with a shaft provided at one end with a gearing engaging said double gearing and at the other with a beveled pinion engaging a beveled pinion upon a cross-shaft provided with a screw-thread, and a sector 50 rigidly attached to the front axle and provided with teeth engaging said screw-thread, all substantially as shown.

14. In a car or vehicle, a power-supplying 55 shaft supported by brackets attached to the bed-plate, provided with a double friction-gearing longitudinally adjustable upon said shaft by means of a sleeve or collar and supporting-springs and a lever connected with 60 said sleeve or collar, in combination with a shaft provided at one end with a frictional gearing engaging said double frictional gearing and at the other end with a bevel-pinion engaging a beveled pinion upon a cross-shaft

provided with a screw-thread, and a sector 65 rigidly attached to the front axle and provided with teeth engaging said screw-thread, all substantially as shown.

15. The combination of a power-supplying 70 shaft provided with a longitudinally-adjustable double frictional gearing with a shaft provided with a frictional pinion and a screw-thread, a spur-wheel engaging said screw-thread and carrying on the same shaft a sprocket-wheel, and a chain operated by said 75 sprocket-wheel, its respective ends connected to the ends of the front axle near the wheels, whereby the line and direction of the front axle and wheels may be changed, all substantially as shown. 80

16. In a car or vehicle, a double frictional gearing provided with a hollow hub, a sliding ring or collar of said hub, with means for connecting the same to a rod and lever, two springs located on said hub on opposite sides of said 85 ring or collar, the bore of said hub being provided with a spline or groove, all substantially as shown.

17. In a car or vehicle, a double frictional gearing provided with a hub having a hollow 90 bore and provided therein with a groove or spline, a sliding ring or collar on said hub, with means for connecting the same to a rod and lever, anti-frictional rollers on each side of said ring or collar, and two springs located 95 on said hub on opposite sides of said ring or collar, and rollers, all substantially as shown.

18. In a car or vehicle, a bed-plate supported on the two axles thereof and their wheels, the rear axle provided with a gear-wheel, in combination with a power-supplying shaft having a pinion engaging with gear-wheel, an adjustable clutch operated by a lever, whereby said pinion and gear-wheel may be made to operatively engage and disengage, and means 100 for operating and revolving said power-supplying shaft and the devices connected therewith, all substantially as shown. 105

19. In a car or vehicle, a bed-plate supported by collars or hangers on the rear axles and its 110 wheels and pivotally attached to the front axle and its wheels at and above the center of said axle, said axles each provided with a gear-wheel, in combination with two gear-wheels supported in journals and located, respectively, above the centers of each axle, and means for connecting said last two gear-wheels and transmitting the motion of one to the other, whereby the motion or revolutions 115 of the gear-wheel of one axle are communicated to that of the other unaffected by any change of direction of such other axle, all substantially as shown. 120
